US0D1042564S

(12) **United States Design Patent** (10) Patent No.: **US D1,042,564 S**
(45) Date of Patent: ** Sep. 17, 2024

(54) **ROTARY GRIP**

(71) Applicant: **LensDigital, LLC**, Old Bridge, NJ (US)

(72) Inventor: **Leonid Karchevsky**, South River, NJ (US)

(73) Assignee: **LensDigital, LLC**, Old Bridge, NJ (US)

(**) Term: **15 Years**

(21) Appl. No.: **29/926,468**

(22) Filed: **Jan. 30, 2024**

Related U.S. Application Data

(63) Continuation of application No. 29/898,469, filed on Jul. 27, 2023, now Pat. No. Des. 1,013,005.

(57) **CLAIM**

The ornamental design for a rotary grip, as shown and described.

DESCRIPTION

FIG. 1 is a top, front, left-side, perspective view of a rotary grip;

FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The broken lines are included for the purpose of illustrating portions of the rotary grip and form no part of the claimed design.

1 Claim, 6 Drawing Sheets
